UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,058, dated September 9, 1902.

Application filed July 29, 1902. Serial No. 117,577. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front view.

The leading features of the design consist in a frame the sides of which are constituted of columns of a conventional Egyptian style. The cross-piece is in the shape of a hood, with inclosing scrolls meeting at the center thereof and drapery depending from the scrolls and caught up at the center. The center or summer front bears the representation of an Egyp-

tian scene, in the front of which are seen two camels, one standing and the other lying down, the one standing bearing a rider, the figure of a man being shown in a reclining posture at the side of the other camel. In the background of the scene is a representation of the Sphinx and of the Pyramid of Cheops and at one side two palm-trees.

I claim—

The ornamental design for a fireplace-front as herein described and shown.

In testimony whereof I have hereunto set my hand in the presence of two subscribing witnesses.

THOMAS M. DUDGEON.
